R. G. MARSH

SODA FOUNTAIN

Filed May 9, 1924

Inventor:

Robert George Marsh

Batchell & Ricket

Attorneys

UNITED STATES PATENT OFFICE.

ROBERT GEORGE MARSH, OF DETROIT, MICHIGAN.

SODA FOUNTAIN.

Application filed May 9, 1924, Serial No. 712,173.

To all whom it may concern:

Be it known that I, ROBERT GEORGE MARSH, a citizen of the United States, residing at Detroit, in the county of Wayne 5 and State of Michigan, have invented certain new and useful Improvements in Soda Fountains, of which the following is a specification, reference being had therein to the accompanying drawings.

10 This invention relates to soda fountain equipment and more particularly to an arrangement of the packers or cans in which the icecream is packed and from which it is served, these packers being contained 15 within a tank or receptacle for holding a refrigerating agent to keep the cream in frozen condition.

Under present day conditions where floor 20 space is so valuable that every foot of space saved means a very material saving, it is found that the present day equipment not only takes up an unnecessary amount of space but is not sufficiently compact to contain all the equipment necessary within a 25 small space and with a handy arrangement. It is the usual practice to provide a tank or container for holding a refrigerating medium such as ice or brine and to provide within this container a series of cans or holders 30 for receiving icecream packers or cans within which the icecream is packed and from which cans the cream is served directly to the customer. These holders and packers are usually arranged in a single row or rows 35 within the tank and where a considerable number of these packers are required to hold the different kinds of flavors of ice-cream, and ice cream put up in different forms, it is necessary where a single row of 40 packers is provided that this row extends for a considerable distance thus requiring a long tank and necessitating the travel of the person serving the ice cream, back and forth along this tank. Where a plurality of 45 rows of packers are provided in order to get the desired number within a tank of reasonable length, the tank must necessarily be of considerable width, thus taking up valuable 50 floor space inwardly from the wall of the store and where the store, as in many cases is only a few feet wide or where the space available for the fountain equipment is limited in width, this extra width of tank 55 is very undesirable.

Further where the refrigerant tank forms a part of the soda fountain, or dispensing

counter, and where such counter is provided with the usual fountain fixtures, flavoring receptacles, etc., this equipment and flavoring receptacles are usually placed 60 above the refrigerant tank at the rear side of the tank, and as they cannot very well be placed high above the tank as the equipment usually includes a counter over which the ice cream is served, which counter is 65 above the level of the flavoring receptacles, the rear part of the tank over which these receptacles are placed is inaccessible and becomes waste space.

70 The main object of the present invention is to minimize space required in providing for a considerable number of ice cream packers or holders within a refrigerant tank. A further object is to provide an arrangement of packers or holders particularly 75 adapted for application to ice cream soda fountain counters and to facilitate the serving of ice cream from these containers or packers.

80 A further object is to provide an arrangement whereby a plurality of packers are made available for serving therefrom at a single point or station thereby minimizing the work and space required and also increasing the container capacity of a soda fountain of the usual construction. It is also an object of the invention to provide certain other new and useful features in the construction and arrangement, all as hereinafter more fully described.

85 With the above and other ends in view the invention consists in providing a rotary holder for a plurality of packers or ice cream containers with an arrangement thereof within a cooling tank, such as to 90 give a maximum capacity with a minimum space required.

95 The invention further consists in a mechanical construction and arrangement, all as hereinafter more fully described and more 100 fully pointed out in the appended claims, reference being had to the accompanying drawing, in which

105 Figure 1 is a perspective view of a soda fountain with parts broken away and in section to show a rotary holder or container illustrative of the invention, in place therein;

110 Fig. 2 is a transverse vertical section through the fountain shown in Fig. 1;

Fig. 3 is a perspective view of the rotary holder or container, and

Fig. 4. is an inverted plan view of the holder shown in Fig. 3.

For the purpose of showing an illustrative application of the present invention, a 5 soda fountain of the usual general construction is shown in Figs. 1 and 2 of the drawing, this fountain comprising a suitable cabinet 1 with the upper rear portion thereof provided with fountain fixtures 2 and 10 flavor containing compartments 3. The cabinet is provided with insulated walls forming a tank 4 in which may be placed ice, brine, or any suitable refrigerating agent and the upper front part of the cabinet is 15 provided with a tank 5, a drain board 6 and a detachable cover 7 for the refrigerating compartment or tank in which cover is an opening closed by a detachable lid 8 to give 20 access to an ice cream packer or can placed in the tank below this opening. In a fountain of the size shown, there would ordinarily be one or two packers in the tank, and where the fountain is of greater length, there would be a single row of packers 25 arranged within the tank to be available through openings in the cover 7 adjacent the forward side of the tank and forwardly of the overhanging flavor containing compartments 3. The number of ice cream 30 packers which may be used in a fountain of this type, is limited by the length of the fountain due to the arrangement of the single row of packers, and the comparatively large space toward the rear of the 35 tank from this row of packers, is all lost space as a double row cannot be used for the reason that the second row would come beneath the compartments 3 and would not be accessible.

40 The present invention contemplates the use of a rotary holder for holding a plurality of ice cream packers, this holder being rotatable to move the several packers about a central pivot, and thus bringing the several packers carried by the holder successively beneath the opening in the cover 7, so that all may be accessible for the serving 45 of ice cream therefrom through the single opening in the cover. A minimum of horizontal space is taken up by a plurality of packers, by arranging them in a group of three, thus bringing these packers into the most compact relation as they are always of cylindrical form and by the arrangement of the three cylinders about the central turning point, they are in closed relation with but a small central space between the adjacent sides of the three cans. The holder therefore preferably comprises 50 three cylindrical receptacles 11 which are of the proper diameter to receive the usual ice cream containers or packers 14 and these three receptacles are rigidly connected together at their upper ends by a top plate or disk 12 through which the upper ends of

the receptacles open. The three receptacles are rigidly secured together at the lower ends in any suitable manner as by a plate 9 riveted or otherwise secured over the triangular space between the three receptacles and this plate is provided with an opening to receive the lower end of a rod 15 which extends upwardly through the top plate 12, said rod being located in the center of the triangular space between the receptacles to 70 form an axis about which the receptacles may rotate concentrically. To support the receptacles upon the bottom of the tank 4, each receptacle at its outer side is provided with an anti-friction roller or wheel 10 carried by the can in any suitable manner to turn freely and roll upon the bottom of the tank. The upper end of the rod 15 extends through an opening in the cover 7, said opening forming a guide to locate the holder so that one of the receptacles 11 will be 75 directly beneath the opening in the cover which is closed by the lid 8 and upon rotation of the holder any one of the three receptacles will be brought into position beneath the opening so that ice cream may be served from any one of the packers through this opening. To facilitate the rotation of the holder a crank handle 16 may be provided upon the upper end of the rod 15.

With this arrangement three ice cream packers are located within the tank and made accessible through a single opening in the cover where ordinarily only one packer is placed and the space within the tank which is taken up by the two additional packers is the space which is ordinarily waste space within the tank as it is beneath the compartments 3. A minimum of space with a maximum capacity is therefore secured by this arrangement and as the capacity is trebled without materially increasing the size of the tank required, a large number of kinds of ice cream may be stored, and within a tank of comparatively short length, thus saving a great deal of labor in connection with the serving of ice cream from these packers.

As the arrangement of packers in groups of three and rotating these packers about a center point of the group, is the most compact arrangement that can be had, a great deal of space may be saved in a cooling tank of any type whether used in connection with a soda fountain equipment or not, by employing this arrangement, and the desired number of packers are made available in a tank of both minimum width and length. Further as three packers are made accessible through a single opening in the cover, much time is saved as it is necessary to remove but a single cover instead of being obliged to remove three covers or one for each packer as in the usual construction. And further the contents of the tank are exposed to the

outside atmosphere through less openings upon removal of the covers than in the usual arrangement.

While a particular construction of rotary holder or stand has been shown, and while in the accompanying drawing there is illustrated a preferred embodiment of my invention, it will be understood that the structural elements are susceptible to such modifications as fall within the scope of the appended claims.

Having thus fully described my invention what I claim is:

1. The combination of a receptacle for a refrigerant a detachable cover for said receptacle provided with a small opening and a large opening, a rotary holder within the refrigerant receptacle to receive and hold a plurality of ice cream containers, said holder including a rod extending through the small cover opening and adapted to be rotated to bring the containers successively beneath the large opening in the cover.

2. An ice cream container holder comprising cylindrical receptacles, a top plate con-

necting said receptacles, a bottom plate connecting said receptacles, and a rod connecting said top and bottom plates and extending above said top plate so as to facilitate rotation of said holder.

3. In a soda fountain structure wherein a tank contains a refrigerant material and soda fountain fixtures overhanging the rear portion of said tank; means for rotatably supporting icecream containers in said tank so that said containers may be swung under the fountain fixtures, said means comprising a plurality of cylindrical receptacles, a top plate securing the upper ends of said receptacles together to rotate about a central vertical axis, and means extending from said tank for rotating said top plate to bring the receptacles successively into position at the front portion of said tank.

In testimony whereof I affix my signature in presence of two witnesses.

ROBERT GEORGE MARSH.
